THERMOSTAT CONTROL CASE

Paul H. Harrison, Los Angeles, and Norman E. Roe,
Sierra Madre, Calif., assignors to Robertshaw Controls
Company, a corporation of Delaware

Filed July 31, 1962, Ser. No. 71,119

Term of patent 14 years

(Cl. D52—6)

FIG.1.

FIG.2.

FIG.3.

FIG.4.

FIGURE 1 is a front perspective view from one side of a thermostat control case showing our new design;

FIGURE 2 is a top plan view of the same;

FIGURE 3 is a front view of a thermostat control case according to our design;

FIGURE 4 is a side view of the thermostat control case as viewed from the side opposite that illustrated in FIGURE 1; and

FIG. 5 is a side elevational view thereof, as viewed from the left of FIG. 1.

The rear of the thermostat control case is conventionally plain and the front face includes a screen grid area.

We claim:

The ornamental design for a thermostat control case, as shown and described.
